(57) **CLAIM**

The ornamental design for a dispenser for dental use, as shown and described.

DESCRIPTION

FIG. 1 is a right side perspective view of a dispenser for dental use showing my new design;

FIG. 2 is a front and left side perspective view thereof;

FIG. 3 is a bottom perspective view thereof;

FIG. 4 is a left side perspective view thereof showing the tube in an extended position; and,

FIG. 5 is a bottom perspective view thereof.

The broken lines in the figure drawings are for illustrative purposes only and form no part of the claimed design.
